UNITED STATES PATENT OFFICE.

FRANKLIN J. PERKINS, OF WOBURN, MASSACHUSETTS, ASSIGNOR TO HOLDER-PERKINS COMPANY, OF WOBURN, MASSACHUSETTS, A CORPORATION OF MASSACHUSETTS.

PUMP.

1,002,306.

Specification of Letters Patent.

Patented Sept. 5, 1911.

Application filed March 29, 1911. Serial No. 617,660.

To all whom it may concern:

Be it known that I, FRANKLIN J. PERKINS, a citizen of the United States, residing in Woburn, county of Middlesex, and 5 State of Massachusetts, have invented an Improvement in Pumps, of which the following description, in connection with the accompanying drawings, is a specification, like letters on the drawings representing 10 like parts.

This invention relates to a pumping apparatus and is herein shown as embodied in an apparatus with which a substantially high pressure may be obtained in an accumulator or other tank or vessel in a minimum time, and with a prime mover for the pump of minimum size and capacity.

The pumping apparatus herein shown is provided with a plurality of cylinders of 20 various sizes, which are connected with the pressure tank to discharge fluid therein, and provision is made for automatically disconnecting some of the cylinders individually from the pressure tank when the pressure 25 in the latter reaches successive predetermined points. The cylinders of the pump may and preferably will be arranged tandem and made of different areas or sizes, as will be described, and the cut-out for each 30 cylinder is arranged so that the cylinders may be successively disconnected from the pressure tank beginning with the cylinder of largest size. These and other features of 35 this invention will be pointed out in the claims at the end of this specification.

Figure 1 is a side elevation of one form 40 of pumping apparatus embodying this invention. Fig. 2, a vertical longitudinal section of the pump portion of the apparatus shown in Fig. 1. Fig. 3, an end elevation of the pump portion of the apparatus shown in Fig. 1 looking toward the left, and Fig. 4, a detail in section on an enlarged scale 45 of one of the automatic cut-outs to be referred to.

In the present instance, the invention is shown as embodied in a pumping apparatus provided with four cylinders 1, 2, 3, 4, arranged in tandem and of different sizes, 50 which successively decrease from the cylinder 1 to the cylinder 4. The cylinders 1

to 4 have located in them pistons or plungers 5, 6, 7, 8, which may be detachably secured together or may be made as one piece with the piston rod 9 of a steam engine 10 55 of any suitable construction.

The pump cylinders 1 to 4 are made individual as herein shown, and secured together by bolts 12 in a manner well understood. Each pump cylinder is provided 60 with a fluid inlet and with a fluid outlet, and in the present instance the fluid inlet passage 13 for each cylinder is connected with a supply chamber 14, which is connected by a pipe 15 with the source of fluid 65 supply, which is represented in Fig. 1 as a tank or vessel 16. Communication between each fluid inlet passage 13 and the supply chamber 14 is controlled by a check valve 18, which is arranged to be opened on the 70 suction stroke of the piston in the cylinder with which the inlet passage is connected near its front end as herein represented, and each cylinder is provided near its front end with an outlet port 20 controlled by a 75 check valve 21, which is arranged to be held to its seat on the suction stroke of the piston and to be opened on the discharge stroke of the piston. The valves 21 of the cylinders 1 to 4 inclusive control communication 80 between the said cylinders and their outlet passages 25, 26, 27, 28, which are individually connected with an accumulator or other closed tank or vessel 29, in which it is desired to accumulate the fluid under 85 pressure. The outlet passages 25, 26, 27, have connected with them valve casings 30, 31, 32, each provided with outlet ports 33, 34, which are connected by pipes 35, 36, with the accumulator 29, and the outlet 90 passage 28 is connected by a branch pipe 37 with the pipe 35.

Each of the valve casings 30, 31, 32, is provided with a valve controlling the ports 33, 34, said valve in the present instance being 95 shown as a hollow cylinder 40, open at its lower end and closed at its upper end, and provided in its body portion with slots 41, 42, forming ports, which are designed to connect the interior of the valve with the 100 pipes 35, 36, as will be described. The valve 40 is normally held up in its casing against

a stop 45 (see Fig. 2) by a spring 46, encircling a rod 47 attached to the valve and extended through the closed upper end of the valve casing, said spring bearing against a 5 collar 48, which is adjusted on the rod 47 by nuts 49 engaging the threaded end of the said rod. The valve casing has communicating with it above the valve 40 in its uppermost position, a pipe 50, which leads to the upper 10 part of the accumulator, so that the valve is subjected to the pressure within the accumulator at all times. When the pressure is below a predetermined point, which is determined by the adjustable nuts 49 acting 15 on the spring 46, the latter overcomes the pressure on the upper surface of the valve and lifts the latter against its stop, and when the valve is in this position, the port 41 registers with the mouth of the port 33, thereby connecting the valve casing with the 20 pipe 35, and the port 42 is out of line with the port 34, and communication between the valve casing and the pipe 36 is cut off. When, however, the pressure on the top of 25 the valve exceeds the tension or pressure of the spring 46, the valve 40 is moved down in its casing and the port 42 is brought into register with the port 34, and the port 41 is moved out of register with the port 33 and 30 communication between the valve casing and the pipe 35 is cut off and established between said casing and the pipe 36. With the valves in the position shown in Fig. 2, all four pistons are working simultaneously to force the 35 fluid into the storage tank or accumulator, each piston on its suction stroke drawing water or other fluid from the supply tank 16 into its cylinder, and on their discharge stroke, the pistons 5, 6, 7 force the water up 40 into their valve casings and through the ports 41, 33 into the pipe 35 and thence into the accumulator 29, while the piston 8 forces the water through the branch pipe 37 into the pipe 35 and thence into the accumulator. 45 After the pressure in the accumulator has been raised therein to a predetermined point, the valve 40 connected with the largest pump cylinder 1 is moved by said pressure to cut off the pipe 35 and connect the pipe 36 with 50 the valve casing, the force or tension of the spring 46 for said valve being adjusted to be overcome at the predetermined pressure. The pump continues to run but the piston area, which is effective for forcing the water 55 into the accumulator has been materially reduced, for instance, about one-half; that is, piston 5 in the largest cylinder 1 reciprocates in unison with the other pistons and draws liquid from the supply as above described, 60 on its suction stroke, and on its discharge stroke, the liquid is returned to the supply tank, it passing from the valve casing 30 through the ports 42, 34 into the pipe 36, which returns it to the supply tank. The large

cylinder 1 is thus practically cut out, and 65 the reduced area of the remaining pistons, being less than the maximum area which the steam engine initially took care of, enables the steam engine to work the three remaining pistons against the pressure in the 70 accumulator. The pressure in the accumulator is thus raised until it reaches a higher predetermined point, at which time the said pressure operates the valve 40 connected with 75 pump cylinder 2 to connect the valve casing with the supply tank, thereby automatically cutting out the next largest cylinder. The pump continues to run and the pistons 7, 8, remain effective for forcing liquid into the pressure tank against a considerable 80 pressure therein, and the pump pistons 7, 8, remain effective until the pressure in the accumulator reaches a third point, whereupon the valve 40 connected with the third cylinder 3 is moved by the pressure in the accumulator 85 so as to cut out this pump cylinder and connect it with the supply tank. The pump continues to run with the piston area of the fourth and smallest cylinder 4 as the effective piston area, and liquid is forced into the 90 accumulator until the pressure therein reaches a fourth predetermined point, at which the pressure in the accumulator becomes equal to the capacity of the piston 9 and holds the check valve 21 closed with the 95 result, that the pumps are stopped until the pressure in the accumulator has been reduced as by use, whereupon the piston 8 is again rendered active. If the pressure in the accumulator is reduced below the third predetermined point, the pistons 7, 8, automatically 100 become effective, and when said pressure is reduced to below the second and first predetermined points, the three pistons 6, 7, 8, and then the fourth, 5, becomes effective. As soon 105 as the pressure falls below the third point, the valve 40 for the cylinder 3 is moved by its spring 46 to cut off the pipe 36 from the cylinder 3 and connect the latter with the pipe 35 leading to the accumulator. When the 110 pressure falls below the second predetermined point, the spring 46 moves the valve 40 of the second cylinder 2 so as to cut off the pipe 36 and connect the pipe 35. When the pressure falls below the first or lowest 115 predetermined point, the spring 46 moves the valve 40 for the first cylinder and cuts off the pipe 36 and connects the pipe 35.

I have herein shown the pump pistons as operated by a steam engine, but it is not desired to limit the invention to any particular form of prime mover for the pump pistons.

In practice a single tandem pump may be used with the accumulator or a duplex tandem may be used after the manner represented in Fig. 3.

I have herein shown the tandem pump

as comprising four cylinders and pistons, but it is not desired to limit the invention to any particular number of the cylinders in the tandem.

5 The invention is represented in one form or construction, which may be preferred, but it is not desired to limit the invention to the particular construction herein shown.

From the above description, it will be seen that when all four pistons are in operation to force liquid into the accumulator, the latter will be filled to a predetermined point in a substantially short time, and thereafter a greater pressure in the accumulator is obtained with the prime mover whose size and capacity remain the same. In other words by diminishing the piston areas by successive steps, the back pressure from the accumulator acting against the pistons of the pump does not overcome the direct pressure of the prime mover, and as a result a high pressure in the accumulator is obtained in a minimum time with a prime mover of minimum size or capacity, which is operated in an even or uniform manner.

A pumping apparatus embodying this invention is easy running and economical, and can be installed at a low cost and maintained in effective condition at a minimum expense. The pistons or plungers are rendered fluid tight in their cylinders in any suitable manner as by packing rings 70, which are shown as located in annular grooves in the walls of the cylinders.

35 Claims:

1. The combination with a pressure tank or vessel, of a pumping apparatus comprising a plurality of cylinders and pistons of different sizes and arranged tandem, a fluid inlet for each of said cylinders, a check valve controlling said fluid inlet, a fluid outlet for each of said cylinders, a check valve controlling said fluid outlet, means for connecting the fluid outlets of said cylinders with the said pressure tank or vessel, and valves controlling the passage of fluid from some of said cylinders to said pressure tank or vessel, said valves being actuated by fluid pressure from said tank or vessel when said pressure reaches predetermined points to automatically cut off from said pressure tank or vessel the cylinders of the pump, which are controlled by said valves, substantially as described.

55 2. A pumping apparatus comprising a plurality of cylinders and pistons of different sizes and arranged tandem, a fluid inlet for each of said cylinders, a check valve in said fluid inlet, a fluid outlet for each of said cylinders, a check valve in said fluid outlet, and valve casings connected with the fluid outlets of the larger cylinders and provided with fluid outlet ports, valves in said casings controlling said ports, and means to move

said valves in one direction to close one of 65 said ports and open the other, substantially as described.

3. A pumping apparatus comprising a plurality of cylinders and pistons of different sizes and common means for actuating 70 said pistons and arranged tandem, fluid inlets for said cylinders, fluid outlet pipes for said cylinders and valves in the fluid outlet pipes of some of said cylinders normally open and automatically operated 75 to close said outlet pipes and render ineffective the cylinders of the pump with which they are connected.

4. The combination with a pressure tank or vessel, of a pumping apparatus comprising 80 a plurality of cylinders and pistons of different sizes and common means for actuating said pistons, pipe connections between said cylinders and said pressure tank, and a valve controlling the connection of one of 85 said cylinders with said pressure tank and normally open to establish communication between the same when the pressure in the tank is below a predetermined point, and actuated by the pressure in the tank to 90 cut off said communication when the pressure in the tank reaches said predetermined point, substantially as described.

5. The combination with a pumping apparatus comprising a plurality of cylinders 95 and pistons, and a prime mover for the same, of a pressure tank, fluid outlet pipes for said cylinders connecting the same with said tank, a valve casing having a port connected with one of said cylinders, a second 100 port with which one of the fluid outlet pipes is connected, a valve in said casing controlling said second port and normally open, a pipe connecting the pressure tank with the valve casing on the opposite side of the valve 105 from the port connected with the pump cylinder to enable said valve to be closed by fluid pressure when the said pressure in the tank reaches a predetermined point, and means to open said valve when the pressure 110 falls below said predetermined point, substantially as described.

6. The combination with a pumping apparatus comprising a plurality of cylinders and pistons, a pressure receptacle, a fluid 115 supply, means for connecting the pump cylinders with said supply, outlet pipes for said cylinders connected with said pressure receptacle, a valve casing having a port connected with one of said cylinders, and having 120 a second port connected with the outlet pipe for said cylinder, and having a third port connected with the source of fluid supply, a valve in said casing, means for holding said valve in a position to normally open the port connected with the said outlet pipe and to close the port connected with the fluid supply, and

means to connect the valve casing with the pressure receptacle to enable the pressure in said receptacle to move the valve and close the fluid outlet pipe of the pump cylinder 5 and open the port connected with the source of fluid supply, substantially as described.

In testimony whereof, I have signed my

name to this specification in the presence of two subscribing witnesses.
